FIG. 4.

UNITED STATES PATENT OFFICE.

JOHN WALDHEIM, OF NEWARK, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

1,054,725.

Specification of Letters Patent.

Patented Mar. 4, 1913.

Application filed March 11, 1912. Serial No. 682,941.

To all whom it may concern:

Be it known that I, JOHN WALDHEIM, citizen of the United States, and resident of Newark, in the county of Essex and State 5 of New Jersey, have invented certain new and useful Improvements in Type-Writing Machines, of which the following is a specification.

My invention relates to typewriting machines and more particularly to means for controlling rotative movements of the platen for billing and like purposes.

The main object of the invention, generally stated, is to provide efficient mechanism by which rotative movements of the platen may be readily effected, and the extent thereof determined with mechanical accuracy to properly introduce work sheets in the machine without burdening the mind 20 of the operator with calculations, and without the necessity of inspecting index devices, etc.

Other objects of my invention, considered from a more specific point of view, are to provide a construction in which the platen may be rotated by means of a spring to bring a work sheet into position to receive the first writing line, for example; to lock a hand actuated device or crank arm, by 25 which the platen is controlled, against operation until the platen has been operatively connected therewith; to automatically release said lock when operative connection between the hand actuated device and platen 30 is effected; to lock said hand actuated device against return movement under the power of its spring so that a work sheet may be properly inserted before the return movement of the platen takes place; to provide efficient means by which an incomplete 35 rotation of said hand actuated member is operative to effect more or less than a single rotation of the platen as may be desired; and to provide means whereby a single continuous stroke of a member is effective to 40 automatically release the lock which holds the hand actuated device against movement, to operatively connect said device with the platen and to move said device and thus 45 turn the platen a predetermined distance.

To the above and other ends which will hereinafter appear, my invention consists in the features of construction, arrangements of parts and combinations of devices set 50 forth in the following specification and par-

ticularly pointed out in the appended claims.

In the drawings wherein like reference characters indicate corresponding parts in the various views, Figure 1 is a side view 60 showing the upper portion of one form of typewriting machine embodying my invention, parts being omitted and sectioned away. Fig. 2 is a plan view of the same with parts in section. Fig. 3 is a detail side view 65 of the stop carrying segment or index plate. Fig. 4 is a fragmentary detail side view of certain of the devices embodying my invention together with some of the parts with which they coöperate. Fig. 5 is a like view 70 of the same but showing a different disposition of the parts. This view corresponds substantially to a section taken on the line $x-x$ of Fig. 6 and looking in the direction of the arrow at said line. Fig. 6 is a frag- 75 mentary transverse sectional view of the parts represented in Fig. 5, the section corresponding substantially to a section taken on the line $y-y$ of Fig. 5 and looking in the direction of the arrow at said line. Fig. 7 80 is a detail fragmentary side view showing the lower or pivoted end of the hand actuated device or crank arm by which the platen is rotated. Fig. 8 is a detail per- 85 perspective view of a rotative carrier which carries certain members of the planetary gearing. Fig. 9 is a detail fragmentary sec- 90 tional view of parts of the mechanism represented in Fig. 6, the section being taken on the line $z-z$ of Fig. 6 and looking in the direction of the arrow at said line; the parts however being disposed as they are represented in Fig. 1.

I have only shown so much of a typewriting machine as may be necessary to arrive 95 at an understanding of my invention in its embodiment therein.

In the present instance I have shown my invention embodied in a Monarch machine, although it will be understood that the invention may be embodied in various styles 100 of typewriting machines in which rotative platens are employed.

The top plate 1 of the machine is supported by corner posts 2, and uprights or 105 brackets 3 are secured to the top plate. These brackets constitute supports for oppositely grooved fixed guide rails 4 in the oppositely grooved faces of which anti-friction balls or rollers 5 are received. A guide 110

bar 6 is provided with oppositely grooved rails 7 which likewise receive anti-friction balls or rollers 5 in the grooved faces thereof. This guide bar constitutes a rear cross bar of a carriage from which project forwardly extending end bars or plates 8 and 8^a, apertured to provide journal bearings for a platen shaft 9 on which a cylindrical platen 10 is mounted. The carriage is thus mounted for movement over the top plate of the machine in the usual manner.

A finger piece 11 is operatively connected to a line spacing pawl 12 coöperative with the crown teeth 13 of a line spacing wheel 14 fixed to one end of the platen or forming part of one of the platen heads. A spring pressed detent roller 15 is pivoted on a leaf spring 16 fixed by a screw 17 to the carriage and this detent roller bears against the line spacing teeth. Any suitable number of line spacing teeth 13 may be provided on the line spacing wheel. In the present instance I have assumed that the line spacing wheel is provided with thirty-three teeth, the number most commonly used.

The construction thus far described constitutes part of the ordinary equipment of the Monarch machine.

In the present instance the platen shaft 9 at its right-hand end terminates a short distance beyond the outside of the end plate 8, as shown in Fig. 6, and the various devices which constitute part of the billing mechanism are in the nature of an attachment which may be readily connected to and disconnected from the machine; operative connections between said devices and the platen being effected through the right-hand end of the platen shaft 9 as represented in Fig. 6. Thus an extension piece 18 is apertured at one end to receive the right-hand end of the platen shaft and a set screw 19 is received in a tapped opening in the extension piece and bears at its inner end against the platen shaft to effect a positive connection between the extension and the platen shaft. The outer end of the extension piece 18 receives a finger wheel 20 secured to the extension piece by a set screw 21 received in a tapped opening in the hub 22 of the finger wheel and bearing at its inner end against the extension piece to fixedly connect the finger wheel with said extension. A segmental stop carrier which is designated as a whole by the reference numeral 23 is shown in detail in Fig. 3. This carrier is in the nature of a bracket which is provided with an arm 24 that extends toward the end plate 8 and terminates in a foot piece 25 by which the member 23 is secured to the end plate 8 of the carriage with the aid of a headed screw 26. A second bracket arm is also provided with a foot piece 27 secured by a screw 28 to the end plate 8. The member 23 is apertured at 29 to receive the ex-

tension 18 which passes freely therethrough. The body portion of the member 23 bears against a shoulder 30 formed by an enlargement 31 on said extension, as shown in Fig. 6. A segmental flange 32 extends along the upper edge of the member 23 and this flange is provided with two series of engaging openings 33 and 34, the openings of one series being staggered relatively to the openings of the other series. Thus, from an inspection of Fig. 2, it will be seen that each opening 33 is situated in line with the body portion of the flange between two adjacent openings 34. A scale 35 extends along one edge of the segmental flange and each index mark of the scale applies to one of the openings, alternate index marks applying to adjacent openings of the same series. Thus in the present instance sixty-six openings 33 and 34 have been provided and there are sixty-six index marks on the scale. It will be understood that by this arrangement a comparatively fine adjustment along the scale may be provided, and the adjusted part may be secured in its adjusted position in the openings 33 or 34 without the necessity of making the openings so small that they might be ineffective to properly secure the adjusted part in position. The part 23 has been referred to as a stop carrier and its purpose, or one of its purposes, is to provide means by which an arresting stop may be adjustably secured thereto. A stop carrying arm 36 is apertured at its lower end to receive a reduced bearing portion 37 of the platen shaft extension 18 as shown in Fig. 6. The upper end of this stop carrying arm is provided with an overlapping portion 38 which extends to the left and overlies the segmental portion 32 of the stop carrier 23 as shown in Figs. 2 and 6. This portion 38 of the stop carrying arm is apertured to receive two spring pressed locking bolts 39 and 40. Each bolt is provided with a flange 41 against which an expansion spring 42 bears, the upper end of each spring bearing against a bottom wall of a recess in which the spring is contained. A plate 43 is apertured to receive the bottom end of the locking bolts 39 and 40 and to provide a bearing surface for the flanges 41. This plate is connected to a stem 44 which in turn is connected at its upper end to a finger piece 45 by which the plate 43 may be lifted to disengage either of the locking bolts which happens to engage any one of the locking openings 33 and 34. It will be understood that the staggered arrangement of these openings enables but one of the locking bolts at a time to effect an engagement in an opening. Thus if the locking bolt 39 is in engagement in an opening 34 then the bolt 40 will be maintained disengaged and will be held against the face of the seg-

ment 32 on the metal intermediate the two adjacent openings 33. If on the other hand, the locking bolt 40 engages in an opening 33 then the bolt 39 will not register with an opening 34 and it will be maintained against the face of the segment and out of locking engagement.

A slide 46 is slotted as at 47 for the reception of headed pins 48 by which the slide is connected to the stop carrying arm 36 and is adapted to receive a movement thereon in the direction of the length of said arm and toward, and from the axis of the platen. A contractile spring 49 is connected at one end 10 to a pin 50 which projects from said slide and at its opposite end to a pin 51 which projects from the stop carrying arm 36. This spring exerts a force to normally maintain a slide at the end of its movement toward the axis of the platen as represented 15 in Fig. 1. An arresting stop 52 projects laterally from the slide 46 and is knurled at the outer end portion thereof, as indicated at 53, to form a finger piece by which 20 the slide 46 may be moved toward the free end of the stop carrying arm against the power of the spring 49, for purposes which will hereinafter more clearly appear. It 25 will be seen therefore that the stop 52 is an adjustable stop which may be turned with the stop carrying arm 36 around the axis of the platen to any one of sixty-six positions indicated on the scale 35, and may be retained in its adjusted position by one or 30 the other of the locking bolts 39 and 40 engaging in a corresponding opening in the segmental stop carrier or support 23. A second fixed stop 54 projects laterally from one side of the stop carrier 23 to effect an 35 arrest of the forward rotative movement of the platen as will hereinafter more clearly appear.

A hand actuated device or crank arm 55 is apertured at 56 (see Fig. 7) and has a 40 small hub 57 projecting from one side thereof. This hub is received on the reduced portion 37 of the platen shaft extension 18 and is free to turn thereon. The outer or free end of the crank arm is provided with a 45 laterally extending finger piece or handle 58 by which the crank arm may be manipulated. This crank arm 55 is arrested in its rearward movement to normal position by the fixed stop 54 as shown in Fig. 1, and is 50 limited in its forward movement by the adjustable stop 52. From an inspection of Fig. 1 it will be seen that the greatest range of movement of the crank arm from the full line position to the dotted line position 55 is about 120° or about one-third of a complete revolution. Moreover, it will be seen that the crank arm normally rests in the full line position (Fig. 1) and while in such position clears the usual margin stops 59 during the travel of the carriage and in the

dotted line position clears the usual ribbon spools 60 and their holders 61. In no position therefore of the handle or crank arm between the limits of its extreme range of movement does it interfere with any of the 70 parts of the typewriting machine proper, nor does it at any time extend to a point below the upper surface of the top plate. It follows therefore that the crank arm may at all times be manipulated irrespective of 75 the position of the carriage in its line of travel.

Multiple gearing is provided intermediate this crank arm and the platen for effecting a greater extent of movement of the platen 80 than is given to the crank arm. Thus in the present instance the construction is such that a complete movement of the crank arm through about 120° from the full line to the dotted line positions shown in Fig. 1 is 85 effective to turn the platen through the multiple gearing a distance corresponding to sixty-six line spaces or two complete revolutions of the platen; it having been assumed that the platen is provided with the line 90 spacing ratchet wheel having thirty-three teeth. Therefore a third of a revolution of the crank arm is effective to transmit two complete revolutions to the platen.

Means are likewise provided which are 95 operable at will to effect an operative connection between the crank arm and platen through the intermediate train of multiple gearing. Thus it will be seen that a plate or disk 62, the outline of which is best shown 100 in dotted lines in Fig. 5 and in full lines in Fig. 9, is provided with ears 63 apertured for the reception of headed screws 64 which pass through spacing sleeves 65 and are received at their threaded ends in tapped 105 openings 64a (Fig. 3) in the stop carrier 23. By this means the plate 62 is fixedly connected to the stop carrier. This plate 62 is apertured centrally for the reception of the greatest reduced portion 66 of the platen 110 shaft extension 18, the shoulder formed by the junction between the parts 66 and 37 of said extension bearing against the plate 62.

From an inspection of Figs. 5 and 9 it 115 will be seen that the plate 62 is provided with an internal segmental rack, or segmentally arranged rack teeth 67, which constitute a fixed rack with which a pinion 68 meshes. This pinion is carried by a spindle 120 69 received in a bearing opening 70 in a carrier 71, which is shown in detail in Fig. 8. This carrier is apertured at 72 for the reception of the smallest reduced portion 66 of the platen shaft extension 18, said carrier being free to turn on said extension. The carrier is also tapped transversely as indicated at 73 for the reception of a screw 74 which extends through the carrier, as shown in Fig. 6, and has its inner end 75 130

seated in an opening 76 (Fig. 7) in the crank arm 55. The carrier is thus connected by the screw 74 for rotative movement with the crank arm whereas the pinion 68 receives a bodily movement with the carrier and crank arm. The bodily movement of the pinion 68 is effective to transmit a rotative movement to said pinion around the axis of its spindle 69 by reason of the engagement of the pinion with the fixed rack 67. The outer end of the spindle 69 has riveted thereto a pinion 77 which meshes with a pinion 78 that turns loosely on the smallest reduced portion of the platen shaft extension 18. The pinion 78 is provided with a hub on which is fixed an arm 79. The length of this arm is such that it extends outwardly beyond the periphery of the plate or disk 62. It will be understood therefore that a rotative movement of the crank arm 55 is effective to transmit a rotative movement to the spindle 69 as well as a bodily movement thereof around the axis of the platen shaft, and that this movement is transmitted to the pinion 77 and from the pinion 77 to the pinion 78, and that the arm 79 receives a rotative movement corresponding to that of the pinion 78. This rotative movement of the arm 79 is in the same direction as the crank arm 55 but is at a higher rate of speed, so that, for example, a movement of the crank arm from the position shown in Fig. 1 to that indicated in Fig. 5 is effective to move the arm 79 in a corresponding direction from the position shown in Fig. 1 to that represented in Fig. 5. The outer end of the arm 79 has a pawl or engaging device 80 pivoted thereto by a headed screw 81. This pawl has an engaging nose 82 adapted to be received in any of the thirty-three openings or notches 83 in the periphery of a wheel or disk 84. A spring 85 is fixed at one end, as at 86, to the pawl or engaging device and at its opposite or free end bears against a projection 87 which extends from the arm 79. The tail of the pawl extends beyond the pivot 81 and is provided with a laterally projecting pin 88 for purposes which will hereinafter more clearly appear. It will be understood that the force of the spring 85 is effective to force the engaging nose 82 of the pawl toward the axis of the platen and to seat said engaging nose in any of the locking recesses or openings 83 in the disk 84 with which it registers. The disk or wheel 84 has a hub 89 tapped to receive a screw 90 which bears at its inner end against the platen shaft extension 18 to fixedly connect the wheel 84 to rotate with the platen. It will be understood therefore that when the pawl 80 engages the wheel 84, an operative connection is effected between the crank arm 55 and the platen through the train of intermediate multiple planetary gearing; the

crank arm being connected to the gearing at one end of the train and the arm 79 and pawl 80 being connected to the opposite end of the train of gearing. It will also be understood that when the pawl 80 is disengaged from the wheel 84 the crank arm 55 is disconnected from the platen and a movement of the crank arm at this time is ineffective to transmit movement to the platen.

I have provided simple and efficient means whereby an operative connection can be effected between the crank arm 55 and the platen, and have also provided means whereby this connection must necessarily be effected before movement can be transmitted to the crank arm. Thus it will be seen that a releasing or controlling device, which is designated as a whole by the reference numeral 91, is in the nature of a lever of the first order pivoted to the crank arm on a shouldered pivot screw 92. This lever extends in the general direction of the length of the crank arm and is provided at its outer end with a laterally extending finger piece 93 which, in its movement from the position shown in Fig. 1 to that indicated in Fig. 4, for example, is operative to engage the finger piece 58 on the crank arm so that a further forward movement of the finger piece 93 is effective to carry the crank arm 55 with it around the pivotal axis of the platen. A leaf spring 94 is fixedly connected at one end, as at 95, to the lever 91 and bears at its free end against a pin 96 which extends laterally from the crank arm 55. This spring tends to maintain the lever 91 in its normal position with reference to the crank arm as shown in Fig. 1. From an inspection of this figure it will be seen that the lever is limited in its movement to the normal position by a pin 97 which projects laterally from the crank arm 55. The lower end portion 98 of the lever 91 is arranged substantially in an arc of which the axis of the platen is the center. This arm is bent laterally to provide a contact edge which cooperates with the laterally projecting pin 88 on the tail of the pawl 80 when the parts are in the normal positions shown in Fig. 1. It will be understood that the power exerted by the spring 94 is greater than that exerted by the pawl actuating spring 85 so that when the parts are in the normal position, shown in Fig. 1, the lower end of the lever 91 will bear against the pin 88 and maintain the pawl 80 against the pressure of its spring 85 and out of engagement with the wheel 84. It will be seen therefore that a forward movement exerted on the finger piece 93, when the parts are in the normal positions, will be effective to turn the lever 91 around its pivot 92 and to effect a movement of the lever independently of the crank arm. This movement of the lever is effective to move the engaging

70

80

85

100

105

110

115

120

125

130

portion 98 of the lever away from the axis of the platen and to the position represented in Fig. 4. This movement of the contact arm 98 enables the spring 85 to effect an engagement of the pawl 80 with the wheel 84. This engagement will take place no matter at what line space position the platen has been arrested in, since there are as many engaging notches 83 (thirty-three in the present instance) as there are teeth in the line spacing wheel, so that at any line space position of arrest of the platen one of the notches 83 will be brought into register with the engaging nose 82 of the pawl 80.

In order to insure a proper operative connection being effected between the crank arm 55 and the platen, by releasing the pawl 80 and effecting an engagement between said pawl and the wheel 84 before motion is transmitted to the crank arm 55, I have provided means for locking the crank arm against movement until the crank arm has been operatively connected with the platen. These means in the present instance comprise a locking latch 99 which is in the nature of an angular lever pivoted at 100 on the crank arm 55, and provided with an engaging nose 101 which is adapted to engage one end 102 of the segment 32, when the parts are in normal position, as shown in Fig. 1.

From an inspection of Fig. 2 it will be observed that the engaging portion of the locking pawl 99 is off-set from the body portion thereof. This is in order that the engaging portion of the pawl may coöperate with the end 102 of the segment 32 when the parts are in normal position, or may ride along the upper face of the segment when the locking latch is moved to the releasing position and the crank arm 55 is shifted from its normal position, as will be understood from an inspection of Fig. 4. The control of the locking latch is automatically effected through the actuation of the controlling lever 91. Thus said lever is provided with a laterally projecting pin 103 which extends through a slot 104 (see Figs. 2 and 7) in the crank arm 55. This pin likewise extends through a slot 105 (see Fig. 4) to effect an operative connection between the pawl and the controlling lever 91. It will be understood therefore that when the parts are in the normal positions represented in Fig. 1, the handle or crank arm 55 is locked against actuation by the latch 99, the spring 94 of the actuating lever at this time maintaining such engagement through the connection between the lever and locking latch. When, however, the lever 91 is moved independently of the crank arm 55 from the position shown in Fig. 1 to that indicated in Fig. 4, an operative connection between the crank arm and the platen is effected in the manner hereinbefore described. This same

movement of the lever 91 is effective to move the latch 99 to the position shown in Fig. 4, thereby releasing it from locking engagement with the end 102 of the segment 32. When the finger piece 93 on the controlling lever reaches the position shown in Fig. 4, said finger piece engages the finger piece 58 on the crank arm 55 and a further continuous movement of the finger piece 93 is effective to carry the crank arm 55 along with the lever 91 around the axis of the platen, as shown in Fig. 5. This movement of the parts is effective to bring the locking latch or pawl 99 over the segment 32 which prevents a return movement of the locking latch to its normal position with reference to the crank arm 55, and also prevents a restoration of the controlling lever 91 to its normal position with reference to the crank arm 55. It follows therefore that the relation of the locking latch 99 and lever 91 relatively to the crank arm 55, as the parts are shown in Fig. 5 for example, is maintained throughout the forward and backward strokes of the crank arm 55 and until such time as the crank arm has returned to its normal position shown in Fig. 1. When this position has been attained the locking latch will again engage the end 102 of the segment, and the movement of the locking latch which effects such engagement enables the controlling lever 91 to be restored to its normal position relatively to the crank arm, and enables the pawl 80 to be automatically released from engagement with the wheel 84, thereby automatically disconnecting the crank arm from operative connection with the platen.

I have hereinbefore pointed out that the crank arm is limited in its forward and backward movements by the coöperation of the crank arm with the forward and rear stops 52 and 54 respectively. The crank arm 55 is provided at its forward edge with a hook-like member 106 having a cam face 107. As the crank arm is moved forwardly from its normal position the cam face 107 is eventually brought into engagement with the stop 52. The effect of this engagement is to cam the stop, together with the plate or slide 46 which carries it, upwardly against the power of the spring 49 which tends to normally maintain the stop and plate in the lowermost position shown in Fig. 1. As soon as the bill of the hook 106 passes forwardly beneath the stop 52 the spring 49 becomes effective to move the stop 52 toward the axis of the platen and to seat said stop within the hook as shown in Fig. 5. It will be seen that when the parts are in the positions shown in this figure the forward edge of the crank arm 55 abuts the stop 52 and further forward movement of the crank arm is arrested. At the same time the hook 106 engaging the stop 52 will prevent a re-

70

125

130

turn movement of the crank arm until such time as the stop 52 is lifted with the aid of its finger piece 53 out of engagement with the hook 106. The purpose of this means for locking the crank arm against return movement at the forward end of its stroke will hereinafter more clearly appear.

In the present instance I have provided a spring for effecting a rotative movement of the platen during the billing operation or during the introduction of the sheet into the machine and for feeding or positioning the sheet to receive the first line of writing. Thus it will be seen that a coiled spring 108 is secured at its inner end by a screw 109 to the carrier 71 by which the pinions 68 and 77 are carried. The opposite end of this spring is fastened to a hook-like member 110 carried by a drum or casing 111, the diameter of which corresponds substantially to the diameter of the disk 62. The drum is open at both ends and is seated at one end in the periphery of the disk, preferably by an interlocking engagement with the ears 63 which project therefrom. Headed screws 112 are employed to fasten the drum to the disk 62. In this manner the outer end of the spring is maintained fixed, whereas the inner end thereof is connected to the carrier 71 of the planetary gearing. The force of this spring is exerted through the carrier 71 and the train of multiple gears to turn the crank arm 55 around the axis of the platen to the normal position where it engages the stop 54 as shown in Fig. 1. The power of the spring is also exerted to effect a forward rotative movement of the platen through the tendency of this spring to rotate the arm 79, pawl 80 and the wheel 84 which is engaged by the pawl, it having been previously explained that the wheel 84 is positively connected with the platen. It will be understood moreover that the act of connecting the pawl 80 with the wheel 84 is likewise effective to operatively connect the spring with the platen and to render the power of the spring effective to return the crank arm 55 to its normal position after it has been moved forwardly to wind the spring.

The operation of the construction for condensed billing work, for example, is as follows: The parts being in the normal position shown in Fig. 1, the operator will introduce the condensed record sheet, bill sheet and interposed carbon sheet together into the machine in the usual manner and will turn the platen forwardly a line space distance at a time until the bill sheet has reached a position to receive the first line of writing. The extent of this movement may be assumed to be twenty-five single line spaces, or to correspond to twenty-five teeth of the line spacing ratchet wheel. The operator will then set the stop 52 to the posi-

tion indicated by the index mark which designates twenty-five on the scale 35. This position may be readily attained with the aid of a pointer 113 carried by the stop carrying arm 36. The stop carrier is locked in this position and the operator may then proceed to write the bill or invoice, which is reproduced through the interposed carbon on the record sheet. After the bill has been completed the operator will line space, say, twice in order to effect a proper space on the record sheet between the copy of the last written bill and the beginning of the next

to be reproduced on the record sheet. The written bill sheet may then be removed without disturbing the carbon or record sheet.

The operator may then grasp the handle 93 and move it forwardly. The first portion of this movement, as hereinbefore explained, is effective to operatively connect the crank arm with the platen and to release the locking latch 99 which holds the crank arm 55 against movement. When the finger piece 93 engages the finger piece 58 on the crank arm the two members 91 and 55 will move together until the parts are arrested by the engagement of the crank arm with the stop 52. The effect of this engagement is to bring about an automatic locking of the crank arm against return movement and against the power of the spring 108. The forward movement of the members 91 and 55 in the manner just described is effective to wind the spring 108 and to produce a rearward rotative movement of the platen through the multiple gearing, a distance corresponding to twenty-five line spaces. A new invoice or bill sheet may then be introduced, both hands of the operator being free to effect such an introduction of the bill sheet by reason of the fact that the crank arm is locked against return movement by the engagement between the stop 52 and the hook 106. As soon as the new invoice sheet has been introduced the operator may release the stop 52 from engagement with the hook 106 and the power exerted by the spring 108 will be effective to return the crank arm 55 to normal position and to turn the platen forwardly a distance of twenty-five line spaces to bring the last introduced bill sheet to a proper position where it may receive the first line of writing.

The restoration of the crank arm under the power of the spring 108 is effective, when the crank arm reaches normal position, to automatically bring about a reengagement of the locking latch 99 with the end 102 of the segment and to automatically effect a disengagement of the pawl 80 with the wheel 84. At this time the platen is free to be rotated indefinitely independently of the stop mechanism and independently of the billing devices as a whole, the only part of the billing mechanism turn-

ing with the platen at this time being the wheel 84; all other parts of the billing mechanism remaining at rest. This enables the operator to proceed with the writing of the last, and properly introduced bill sheet, and when this is complete and has been copied, through the interposed carbon on the condensed record sheet the bill sheet may be removed and a new sheet introduced in the 10 manner hereinbefore described.

I have referred herein to the fact that the platen is normally free to be rotated indefinitely. By this and like expressions I mean that normally there is no positive obstruction to limit the rotative movement of the platen, although the usual spring detent 15-16 is employed and normally bears against the line spacing ratchet wheel.

From the foregoing description it will be 20 understood that the construction is such that successive billing sheets may be quickly and accurately introduced and properly positioned with reference to the condensed record sheet with but little effort on the part of 25 the operator and that there is nothing to burden the mind of the operator with in effecting the introduction of successive bill sheets in proper position relatively to the condensed record sheet and in proper position 30 to receive the first line of writing on each of the bill sheets. Thus after the adjustable stop 52 is once set it is merely necessary to pull the handle 93 forwardly by a single continuous stroke when the platen 35 will be turned rearwardly the requisite distance to receive a new bill sheet and the release of the stop 52 from engagement with the crank arm enables the platen to be rotated forwardly the requisite distance to introduce the bill sheet and properly position 40 it with reference to the printing line to receive the first line of writing. These operations may be continued indefinitely or until a condensed record sheet is filled and a new 45 bill sheet, condensed record sheet and interposed carbon sheet may be introduced and written upon as before.

Various changes may be made without departing from the spirit and scope of my invention.

What I claim as new and desire to secure by Letters Patent, is:

1. In a typewriting machine, the combination of a rotative platen, line spacing 55 mechanism, a crank arm, a hand actuated lever which is movable independently of the crank arm and which is also movable with said crank arm, means for locking the crank arm against movement, means controlled by the independent movement of said lever for releasing 60 said crank arm, and means controlled by said crank arm for turning the platen.

2. In a typewriting machine, the combination of a rotative platen, a crank arm, a

hand actuated lever which is movable independently of the crank arm in the same general direction as the crank arm and which is also movable with and is effective to move the crank arm, means for locking said crank arm against movement, the independent movement of said lever being effective to release said locking means, and means controlled by the independent movement of said lever for bringing about an operative connection between said crank arm and the platen, so that a continuous movement of the lever in one direction is effective first to release the locking means and then to operatively connect the crank arm with the platen and then to move the crank arm and thereby turn the platen.

3. In a typewriting machine, the combination of a rotative platen, a crank arm, a hand actuated lever which is movable independently of the crank arm in the same general direction as the crank arm and which is also movable with and is effective to move the crank arm, means for locking said crank arm against movement, the independent movement of said lever being effective to release said locking means, means controlled by the independent movement of said lever for effecting an operative connection between said crank arm and the platen, so that a continuous movement of the lever in one direction is effective to release the locking means and to operatively connect the crank arm with the platen and then to move the crank arm and thereby turn the platen, and means for arresting the rotative movement of the platen when it is turned under control of said crank arm.

4. In a typewriting machine, the combination of a rotative platen, a crank arm, a hand actuated lever which is movable independently of the crank arm and which is also movable with said crank arm, means for locking the crank arm against movement, means controlled by the independent movement of said lever for releasing said crank arm, and means controlled by the independent movement of said lever for effecting an operative connection between said crank arm and the platen.

5. In a typewriting machine, the combination of a rotative platen, a crank arm, a hand actuated lever which is movable independently of the crank arm and which is also movable with said crank arm, means for locking the crank arm against movement, means controlled by the independent movement of said lever for releasing said crank arm, means controlled by the independent movement of said lever for effecting an operative connection between said crank arm and the platen, and means for arresting the rotative movement of the platen when it is turned under control of said crank arm.

6. In a typewriting machine, the combination of a rotative platen normally free

to be rotated indefinitely in either direction, a spring for effecting a rotation of said platen for a plurality of line spaces, said spring being normally disconnected from the platen, and hand actuated means operative at will for operatively connecting said spring with the platen and for turning the platen against the power of said spring for a plurality of line spaces and thereby placing the spring under tension to render it effective to rotate the platen in an opposite direction from that in which it is turned by said hand actuated means.

7. In a typewriting machine, the combination of a rotative platen normally free to be rotated indefinitely in either direction, a spring for effecting a rotation of said platen for a plurality of line spaces, said spring being normally disconnected from the platen, hand actuated means operative at will for operatively connecting said spring with the platen and for turning the platen against the power of said spring and thereby placing the spring under tension to render it effective to rotate the platen in an opposite direction from that in which it is turned by said hand actuated means, and means for arresting the platen after a given extent of rotation thereof.

8. In a typewriting machine, the combination of a rotative platen normally free to be rotated indefinitely in either direction, a spring for effecting a rotation of said platen, said spring being normally disconnected from the platen, means operative at will for operatively connecting said spring with the platen, means for arresting the platen after a given extent of rotation thereof, and means by which the operative connection of the spring with the platen is also effective to render the platen arresting means operative.

9. In a typewriting machine, the combination of a rotative platen normally free to be rotated indefinitely in either direction, a spring for effecting a rotation of said platen for a plurality of line spaces, said spring being normally disconnected from the platen, a hand actuated device for rotating the platen a plurality of line spaces at each actuation, and means operable at will for operatively connecting said hand actuated device and spring with the platen.

10. In a typewriting machine, the combination of a rotative platen normally free to be rotated indefinitely in either direction, a spring for effecting a rotation of said platen, said spring being normally disconnected from the platen, a hand actuated device for rotating the platen, means for arresting the platen after a given extent of rotation thereof, and means operable at will for operatively connecting said hand actuated device and spring with the platen and

for rendering said platen arresting means effective.

11. In a typewriting machine, the combination of a rotative platen normally free to be rotated indefinitely, a spring for effecting a rotation of said platen, a hand actuated device for rotating the platen, means for locking said hand actuated device against actuation, and means operable at will for releasing said locking means and for operatively connecting said hand actuated device and spring with the platen.

12. In a typewriting machine, the combination of a rotative platen normally free to be rotated indefinitely, a spring for effecting a rotation of said platen, a hand actuated device for rotating the platen, means for locking said hand actuated device against actuation, means for arresting the platen after a given extent of rotation thereof, and means operable at will for releasing said locking means and for operatively connecting said hand actuated device and spring with the platen and for rendering the platen arresting means operative.

13. In a typewriting machine, the combination of a rotative platen normally free to be rotated indefinitely in either direction, a spring for effecting a rotation of said platen, said spring being normally disconnected from the platen, a crank arm operative to rotate the platen a plurality of line spaces at each actuation, and means operable at will for effecting an operative connection of said crank arm and spring with the platen.

14. In a typewriting machine, the combination of a rotative platen normally free to be rotated indefinitely, a spring for effecting a rotation of said platen, a crank arm operative to rotate the platen, a finger piece which is movable independently of said crank arm and which is also movable therewith, and means controlled by the independent movement of said finger piece for effecting an operative connection of said crank arm and spring with said platen.

15. In a typewriting machine, the combination of a rotative platen normally free to be rotated indefinitely, a spring for effecting a rotation of said platen, a crank arm operative to rotate the platen, means for locking said crank arm against actuation, a finger piece which is movable independently of said crank arm and which is also movable therewith, and means controlled by the independent movement of said finger piece for releasing said locking means and for effecting an operative connection of said crank arm and spring with said platen.

16. In a typewriting machine, the combination of a rotative platen normally free to be rotated indefinitely, a spring for effecting a rotative movement of said platen,

1. a crank arm operative to rotate the platen, means for arresting the platen after a given extent of rotation thereof, locking means for locking the crank arm against actuation, a finger piece which is movable independently of said crank arm and which is also movable therewith, and means controlled by the independent movement of said finger piece for releasing said locking means and for operatively connecting the crank arm and spring with the platen and rendering the arresting means operative. 70
2. In a typewriting machine, the combination of a rotative platen, normally free to be rotated indefinitely, a spring for effecting a rotative movement of said platen, a crank arm operative to rotate the platen, means for arresting the platen after a given extent of rotation thereof, locking means for locking the crank arm against actuation, a lever which is movable independently of said crank arm in the same general direction as the crank arm and which is also movable with and is effective to move the crank arm, and means controlled by the independent movement of said lever for releasing said locking means and for effecting an operative connection of said crank arm and spring with the platen and for rendering the arresting means operative. 80
3. In a typewriting machine, the combination of a rotative platen, a spring for rotating said platen, a hand actuated device for turning the platen against the power of said spring, said hand actuated device being movable with and independently of the platen, and locking means for locking the hand actuated means against return movement. 85
4. In a typewriting machine, the combination of a rotative platen normally free to be rotated indefinitely, a spring for turning said platen, a hand actuated device for rotating the platen, means operable at will for effecting an operative connection of said hand actuated device and spring with said platen, and locking means for locking said hand actuated device and platen against the power of said spring. 90
5. In a typewriting machine, the combination of a rotative platen normally free to be rotated indefinitely, a spring for turning said platen, a hand actuated device for rotating the platen, means for arresting the platen after a fixed extent of rotative movement thereof, means operable at will for operatively connecting said hand actuated device and spring with the platen and for rendering said platen arresting means operative, and means for locking said hand actuated device and platen against the power of said spring. 95
6. In a typewriting machine, the combination of a rotative platen, a spring returned hand actuated device for turning the platen, means operable at will for operatively connecting said hand actuated device and platen, and locking means for locking the hand actuated device against the power of its spring. 100
7. In a typewriting machine, the combination of a rotative platen, a spring returned hand actuated crank arm for turning said platen, means operable at will for operatively connecting said crank arm with the platen, and automatically operating locking means for locking the crank arm against return movement. 105
8. In a typewriting machine, the combination of a rotative platen, a spring returned hand actuated crank arm for turning said platen, means operable at will for operatively connecting said crank arm with the platen, means for arresting the platen, which arresting means are rendered operative when said crank arm is operatively connected with the platen, and a spring pressed latch which automatically engages said crank arm at the limit of its movement and locks it against return movement under the power of its spring. 110
9. In a typewriting machine, the combination of a rotative platen, a hand actuated crank arm mounted to turn on the axis of the platen, intermediate multiple gearing between said crank arm and platen, a stop coöoperative with said crank arm, and means operable at will for effecting an operative connection between said crank arm and the platen through said multiple gearing. 115
10. In a typewriting machine, the combination of a rotative platen, a hand actuated spring returned crank arm, intermediate multiple gearing between said crank arm and platen, stops coöoperative with said crank arm to limit its back and forth movements, and means operable at will independently of the movement of the crank arm for effecting an operative connection between said crank arm and the platen through said multiple gearing. 120
11. In a typewriting machine, the combination of a rotative platen, a hand actuated crank arm mounted to turn on the axis of the platen, intermediate planetary multiple gearing between said crank arm and platen, and means operable at will for effecting an operative connection between said planetary gearing and the platen. 125
12. In a typewriting machine, the combination of a rotative platen, a hand actuated device which is gripped by the operator and moved for effecting a turning movement of the platen, intermediate multiple gearing between said hand actuated device and platen, and means for compelling an operative connection between said hand actuated device and platen to be effected through said multiple gearing before an operation of the hand actuated device can be effected. 130

28. In a typewriting machine, the combination of a rotative platen, a hand actuated device which is gripped by the operator and moved for effecting a turning movement of the platen, intermediate multiple gearing between said hand actuated device and platen, and means for compelling an operative connection between said hand actuated device and platen to be effected through said 5 multiple gearing before an operation of the hand actuated device can be effected and for automatically rendering said device operative when such operative connection is effected.
29. In a typewriting machine, the combination of a hand actuated crank arm, a rotative platen which is normally free to be rotated indefinitely independently of said crank arm but which is adapted to be rotated thereby, intermediate multiple gearing between said crank arm and platen and through which the platen may be turned by said crank arm, a latch which positively locks said crank arm against actuation when it is in the normal position, controlling 10 means operable at will to effect an operative connection between the crank arm and platen through the multiple gearing while the crank arm remains in the normal position, and means for releasing said locking latch when an operative connection between the crank arm and platen is effected.
30. In a typewriting machine, the combination of a hand actuated crank arm, a rotative platen which is normally free to be rotated indefinitely independently of said crank arm but which is adapted to be rotated thereby, intermediate multiple gearing between said crank arm and platen and 15 through which the platen may be turned by said crank arm, a latch which positively locks said crank arm against actuation when it is in the normal position, controlling means operable at will to effect an operative connection between the crank arm and platen through the multiple gearing while the crank arm remains in the normal position, means for releasing said locking latch when an operative connection between the crank 20 arm and platen is effected, and means for arresting the rotative movement of the platen.
31. In a typewriting machine, the combination of a hand actuated crank arm, a rotative platen which is normally free to be rotated indefinitely independently of said crank arm but which is adapted to be rotated thereby, intermediate multiple gearing between said crank arm and platen and 25 through which the platen may be turned by said crank arm, a latch which locks said crank arm against actuation when it is in the normal position, controlling means operable at will to effect an operative connection between the crank arm and platen through the 30 multiple gearing, means for releasing said locking latch when an operative connection between the crank arm and platen is effected, and means for arresting the rotative movement of the platen, said arresting means being rendered effective by the operative connection of said crank arm with the platen. 70
32. In a typewriting machine, the combination of a rotative platen; a single hand actuated device which may be gripped by the operator and moved to effect a turning movement of the platen and for controlling both the forward and backward rotative movement thereof; intermediate multiple gearing between said hand actuated device and platen and through which the platen may be turned by said hand actuated device; and means for effecting an operative connection between said hand actuated device and the platen through said multiple gearing, said connecting means comprising a wheel, and means adapted to engage said wheel at any line space position in the rotation of the platen and to turn bodily with said 75 wheel.
33. In a typewriting machine, the combination of a rotative platen; a hand actuated device for turning the platen; intermediate multiple gearing between said hand actuated device and platen and through which the platen may be turned both backwardly and forwardly under control of said hand actuated device; and means for effecting an operative connection between said hand actuated device and the platen through said multiple gearing, said connecting means comprising a wheel fixedly connected with the platen, and an engaging device operatively connected with the train of multiple gearing and adapted to engage said wheel at any line space position in the rotation of the platen. 80
34. In a typewriting machine, the combination of a rotative platen, a hand actuated device for rotating the platen, a train of multiple gearing to one end of which train said device is connected, a wheel fixedly connected to said platen, and a pawl operatively connected to the other end of the train of gearing and coöperative with said wheel to 85 operatively connect the wheel and pawl to turn together in both directions and to connect said hand actuated device to the platen. 100
35. In a typewriting machine, the combination of a rotative platen, a hand actuated device for rotating the platen, a train of multiple gearing to one end of which train said device is connected, a wheel fixedly connected to said platen, a pawl operatively connected to the other end of the train of gearing and coöperative with said wheel to 90 operatively connect the wheel and pawl to turn together in both directions and to connect said hand actuated device to the platen. 105
36. In a typewriting machine, the combination of a rotative platen, a hand actuated device for rotating the platen, a train of multiple gearing to one end of which train said device is connected, a wheel fixedly connected to said platen, and a pawl operatively connected to the other end of the train of gearing and coöperative with said wheel to 95 operatively connect the wheel and pawl to turn together in both directions and to connect said hand actuated device to the platen. 110
37. In a typewriting machine, the combination of a rotative platen, a hand actuated device for rotating the platen, a train of multiple gearing to one end of which train said device is connected, a wheel fixedly connected to said platen, and a pawl operatively connected to the other end of the train of gearing and coöperative with said wheel to 100 operatively connect the wheel and pawl to turn together in both directions and to connect said hand actuated device to the platen. 115
38. In a typewriting machine, the combination of a rotative platen, a hand actuated device for rotating the platen, a train of multiple gearing to one end of which train said device is connected, a wheel fixedly connected to said platen, and a pawl operatively connected to the other end of the train of gearing and coöperative with said wheel to 105 operatively connect the wheel and pawl to turn together in both directions and to connect said hand actuated device to the platen. 120
39. In a typewriting machine, the combination of a rotative platen, a hand actuated device for rotating the platen, a train of multiple gearing to one end of which train said device is connected, a wheel fixedly connected to said platen, a pawl operatively connected to the other end of the train of gearing and coöperative with said wheel to 110 operatively connect the wheel and pawl to turn together in both directions and to connect said hand actuated device to the platen. 125
40. In a typewriting machine, the combination of a rotative platen, a hand actuated device for rotating the platen, a train of multiple gearing to one end of which train said device is connected, a wheel fixedly connected to said platen, and a pawl operatively connected to the other end of the train of gearing and coöperative with said wheel to 115 operatively connect the wheel and pawl to turn together in both directions and to connect said hand actuated device to the platen. 130

through said train of gearing, and hand actuated means operable at will to effect an engagement between the pawl and wheel.

36. In a typewriting machine, the combination of a rotative platen, a wheel fixed to rotate with the platen and notched to correspond with the spacing of the teeth of the line spacing wheel, a hand actuated device, a train of multiple gearing intermediate said hand actuated device and said notched wheel, and a pawl connected with said train of gearing and adapted to be connected with said notched wheel so that the two will turn together in both directions and may be disconnected to enable the said wheel to turn independently of the pawl.

37. In a typewriting machine, the combination of a rotative platen; a single hand actuated device which may be gripped by a hand of the operator and moved to effect a turning movement of the platen, the said hand actuated device being operative to control both the backward and forward rotation of the platen; intermediate multiple gearing between said hand actuated device and platen and through which the platen may be turned both backwardly and forwardly under control of said hand actuated device; means for effecting an operative connection between said hand actuated device and the platen through said multiple gearing, said connecting means comprising a wheel, and means adapted to engage said wheel at any line space position in the rotation of the platen and for movement with said wheel in both directions; and normally inoperative means for arresting the rotation of the platen, said arresting means being rendered operative when an operative connection is effected between said hand actuated device and the platen.

38. In a typewriting machine, the combination of a rotative platen; a hand actuated device for turning the platen; intermediate multiple gearing between said hand actuated device and platen and through which the platen may be turned both backwardly and forwardly under control of said hand actuated device; means for effecting an operative connection between said hand actuated device and the platen through said multiple gearing, said connecting means comprising a wheel fixedly connected with the platen, and an engaging device operatively connected with the train of differential gearing and adapted to engage said wheel at any line space position in the rotation of the platen; and normally inoperative means for arresting the rotation of the platen, said arresting means being rendered operative by the engagement of said engaging device with said wheel.

39. In a typewriting machine, the combination of a rotative platen, a hand actuated device for rotating the platen, a train of

multiple gearing to one end of which train said device is connected, a wheel fixedly connected to said platen, a pawl operatively connected to the other end of the train of gearing and cooperative with said wheel to operatively connect the wheel and pawl to turn together, and to connect said hand actuated device to the platen through said train of gearing, normally inoperative means for arresting the rotation of the platen, said arresting means being rendered operative by the engagement of said pawl with said wheel, and hand actuated means operable at will for effecting an engagement of the pawl with said wheel.

40. In a typewriting machine, the combination of a rotative platen, a hand actuated device for turning said platen, locking means for preventing an actuation of said hand actuated device, means operable independently of said hand actuated device for releasing said locking means, means for retaining said locking means out of locking engagement until said hand actuated device has been returned to normal position, and a spring for returning said hand actuated device to normal position.

41. In a typewriting machine, the combination of a rotative platen, a hand actuated device for turning said platen, locking means for preventing an actuation of said hand actuated device, means operable independently of said hand actuated device for releasing said locking means, means for retaining said locking means out of locking engagement until said hand actuated device has been returned to normal position, and means for locking the hand actuated device against return movement when it has reached the limit of its movement away from normal position.

42. In a typewriting machine, the combination of a rotative platen, a hand actuated device for turning said platen, locking means for preventing an actuation of said hand actuated device, means operable independently of said hand actuated device for releasing said locking means, means for retaining said locking means out of locking engagement until said hand actuated device has been returned to normal position, a spring for returning said hand actuated device to normal position, and locking means for locking the hand actuated device against the power of its spring.

43. In a typewriting machine, the combination of a rotative platen; a crank arm pivoted to turn on the axis of the platen; multiple gearing between said crank arm and platen; and means operable at will for effecting an operative connection between said crank arm and platen through said multiple gearing, said connecting means comprising a notched wheel fixed to turn with the platen on the axis thereof, and an

engaging device operatively connected with said multiple gearing and adapted to engage said notched wheel.

44. In a typewriting machine, the combination of a rotative platen; a crank arm pivoted to turn on the axis of the platen; multiple gearing between said crank arm and platen; means operable at will for effecting an operative connection between said

5 crank arm and platen through said multiple gearing, said connecting means comprising a notched wheel fixed to turn with the platen on the axis thereof, an engaging device operatively connected with said multiple

10 gearing and adapted to engage said notched wheel, and means operable independently of said crank arm for bringing about a movement of said engaging device into engagement with said notched wheel.

15 45. In a typewriting machine, the combination of a rotative platen; a crank arm pivoted to turn on the axis of the platen; multiple gearing between said crank arm and platen; means operable at will for effecting an operative connection between said

20 crank arm and platen through said multiple gearing, said connecting means comprising a notched wheel fixed to turn with the platen on the axis thereof, and an engaging

25 device operatively connected with said multiple gearing and adapted to engage said notched wheel; and relatively adjustable stops coöperative with said crank arm.

30 46. In a typewriting machine, the combination of a rotative platen; a crank arm pivoted to turn on the axis of the platen; multiple gearing between said crank arm and platen; means operable at will for effecting an operative connection between

35 said crank arm and platen through said multiple gearing, said connecting means comprising a notched wheel fixed to turn with the platen on the axis thereof, an engaging device operatively connected with

40 said multiple gearing and adapted to engage said notched wheel, and means operable independently of said crank arm for bringing about a movement of said engaging device into engagement with said

45 notched wheel; and relatively adjustable stops coöperative with said crank arm.

50 47. In a typewriting machine, the combination of a rotative platen; stop devices for arresting the rotation of the platen, one of said stops being adjustable; and means for holding the adjustable stop in its adjusted

55 position, said means comprising a member having two series of openings, the openings of one series being staggered relatively to

60 the openings of the other series, two spring pressed bolts each engageable in the openings of but one series, and a single finger piece engageable with both bolts to disengage them from said openings.

65 48. In a typewriting machine, the combi-

nation of a rotative platen; stop devices for arresting the rotation of the platen, one of said stops being adjustable; and means for holding the adjustable stop in its adjusted position, said means comprising a member 70 having two series of openings, the openings of one series being staggered relatively to the openings of the other series, two spring pressed bolts each engageable in the openings of but one series, and each of which bolts may engage in an opening of its series while the other bolt is maintained out of engagement, and a single finger piece coöperative with both bolts to disengage whichever bolt is in engagement. 80

49. In a typewriting machine, the combination of a rotative platen, a crank arm pivoted to turn on the axis of the platen, multiple gearing between said crank arm and platen, a lever pivoted on said crank arm and movable with and independently of said crank arm, a wheel fixed to rotate with the platen and to turn around the axis thereof, and means controlled by the independent movement of said lever for operatively connecting the multiple gearing with said wheel. 85

50. In a typewriting machine, the combination of a rotative platen, a crank arm pivoted to turn on the axis of the platen, multiple gearing between said crank arm and platen, a lever pivoted on said crank arm and movable with and independently of said crank arm, a wheel fixed to rotate with the platen and to turn around the axis thereof, means controlled by the independent movement of said lever for operatively connecting the multiple gearing with said wheel, and means for arresting the rotation of the platen, said actuating means being rendered 95 operative by the operative connection between said wheel and the multiple gearing. 100

51. In a typewriting machine, the combination of a rotative platen, a crank arm pivoted to turn on the axis of the platen, multiple gearing between said crank arm and platen, a lever pivoted on said crank arm and movable with and independently of said crank arm, a locking device for locking said crank arm in the normal position, a wheel fixed to rotate with the platen and to turn around the axis thereof, and means controlled by the independent movement of said lever for releasing said locking device and for operatively connecting the multiple 110 gearing with said wheel. 115

52. In a typewriting machine, the combination of a rotative platen, a crank arm pivoted to turn on the axis of the platen, a multiple gearing between said crank arm and platen, a lever pivoted on said crank arm and movable with and independently of said crank arm, a locking device for locking said crank arm in the normal position, a wheel 120 fixed to rotate with the platen and to tur 125

around the axis thereof, means controlled by the independent movement of said lever for releasing said locking device and for operatively connecting the multiple gearing 5 with said wheel, and means for arresting the rotation of the platen, said arresting means being rendered operative by the operative connection between said wheel and the multiple gearing.

10 53. In a typewriting machine, the combination of a rotative platen, a hand actuated device mounted to turn on the axis of the platen, multiple gearing between said hand actuated device and platen, stop mechanism

for limiting the rotation of the platen, and 15 means operable at will for effecting an operative connection between said multiple gearing and platen, the operative connection of the gearing with the platen rendering said stop mechanism operative. 20
